RANSOM SARGENT, OF NORWICH, VERMONT.

Letters Patent No. 70,628, dated November 5, 1867.

IMPROVEMENT IN ROTARY CAM FOR LOOMS.

The Schedule referred to in these Letters Patent and making part of the same.

TO ALL WHOM IT MAY CONCERN:

Be it known that I, RANSOM SARGENT, of Norwich, in the county of Windsor, and State of Vermont, have invented a new and improved Adjustable Rotary Loom-Cam; and I do hereby declare that the following is a full, clear, and exact description thereof, which will enable others skilled in the art to make and use the same, reference being had to the accompanying drawings, forming part of this specification, in which—

Figure 1 is a side view of my improved rotary cam connected with a loom.

Figure 2, a front end view.

Figure 3, a detached side view.

Figure 4, a side view of the adjustable truck-shaft box detached.

Figure 5, a side view of a single truck or cam-disk detached.

Figure 6, a partial sectional view of a truck detached.

Similar letters of reference indicate like parts.

This invention relates to a new and useful rotary cam for working the treadles of a loom to spring the web, and consists of a series of disks or circular trucks attached to a series of shafts which have their bearings in plates or heads secured to a central shaft, the trucks in the said shafts being set on pins to be movable and adjustable on their shafts in such manner that any one or more may be made to engage with cams on corresponding treadles for working the heddles, and springing the web to suit the pattern of the cloth to be woven.

The object of this improvement is to provide the weaver with the means of readily and quickly adjusting the movements of the treadles, and the springing of the harness to weave various styles of cloth on the same loom, and this object is accomplished by simply adjusting the cam-trucks on the truck-shafts to correspond with the treadles, which should be operated to spring the web as desired, as hereinafter fully described. By this arrangement there is a great saving of friction and power, and also of oil required for oiling the apparatus in general use. In other respects this improvement introduces great economy in the manufacture of textile fabrics.

A represents the frame of an ordinary loom, to which are attached only the heddles B and the treadles C, for the illustration of my invention, with which parts it is immediately connected. On the upper side of each of the treadles is a cam-block, D, with a compound, concave, and convex, or wave-line face, as shown in fig. 1. And over these cam-blocks, on the treadles, is hung a centre-shaft, a, on which are circular heads b, outside of the set of treadles; the said shaft being actuated by gear-wheels a¹ a² from any suitable power. On the face of the heads b are hung truck-shafts c, as many as desired for the work in view. These circular heads b are those usually employed, but in my invention the shafts c are hung in adjustable boxes d, regulated by a set-screw, e, as shown in fig. 4, attached to a segment of the head b', which is secured to the shaft in any suitable manner. On each of the shafts c is secured a circular cam or truck, E, which is held in position on the shaft by a spring-pin, g, that enters any one of a series of holes made in the shaft, corresponding with the treadles, so that the trucks may be shifted readily from one position to another for adjustment to the treadles, as desired, according to the style of cloth to be woven.

It will readily be understood that the number of truck-shafts, and trucks upon them, may be placed around the cam-shaft a, according to the number of the treadles, and that they may be placed in any desired position to work upon the corresponding treadles for springing the web, according to the style of goods being manufactured.

Having described my invention, I claim as new, and desire to secure by Letters Patent—

The rotary loom-cam formed of a centre-shaft, a, provided with heads b', on the periphery of which are hung the truck-shafts c, in the adjustable boxes d, for carrying the adjustable circular cams or trucks E, to operate on the cam-blocks D, placed on the treadles C, constructed, arranged, and operating substantially as and for the purposes herein described.

RANSOM SARGENT.
